RAZOR

Clarence A. Pinkham, Douglaston, and Bartholomew A. Holohan, Kew Gardens, N. Y., assignors to Neipin Manufacturing Company, Inc., Long Island City, N. Y., a corporation of New York

Application July 7, 1953, Serial No. 25,828

Term of patent 14 years

(Cl. D22—3)

To all whom it may concern:

Be it known that we, Clarence A. Pinkham and Bartholomew A. Holohan, citizens of the United States and residents, respectively, of Douglaston and Kew Gardens, both in Long Island, in the county of Queens and State of New York, have invented a new, original, and ornamental Design for a Razor, of which the following is a specification, reference being had to the accompanying drawing, forming part hereof, in which:

Fig. 1 is a perspective view of one end of a razor showing our new design, and

Fig. 2 is a perspective view of the opposite end of the razor shown in Fig. 1.

We claim:

The ornamental design for a razor, substantially as shown.

CLARENCE A. PINKHAM.
BARTHOLOMEW A. HOLOHAN.
